UNITED STATES PATENT OFFICE.

EINAR ERIK ALM, OF STOCKHOLM, SWEDEN.

APPARATUS FOR TARGET PRACTICE WITH RIFLES AND OTHER FIREARMS.

Application filed February 1, 1921. Serial No. 441,705.

To all whom it may concern:

Be it known that I, EINAR ERIK ALM, printing-office superintendent, subject of the King of Sweden, residing at Stockholm, 5 Sweden, have invented certain new and useful Improvements in Apparatus for Target Practice with Rifles and Other Firearms, of which the following is a specification.

In target-practice indoors, the size of the 10 target has to be diminished in the same degree as the fire range is reduced. A precision target with 5 rings, which in reality has a size of 1700 x 1400 millimeters and which is positioned at a distance of 300 meters, at a distance of 30 meters has to be 15 170 x 140 millimeters; at a distance of 3 meters the size of the target will be 17 x 14 millimeters, and so forth. Certain technical difficulties, however, prevent shooting at too 20 small distances.

The apparatus according to the present invention is intended as a substitute for target practice indoors. The novel apparatus makes it possible for the marksman to manipulate the arm in any locality for instance inside the four walls of a room, in a manner approaching natural conditions as nearly as possible, that is, he will be able to aim at a target which is visible to the eye, the same 25 as in bullet practice, and to pull the trigger so as to cause a record to be made on a miniature target, corresponding to the hit of the bullet, if actual target practice had taken place instead.

The invention is principally characterized by a part (the armature) attached to the rifle so as to be movable relatively to the latter in all directions, the said armature being movably connected with a recording device 30 provided in the rifle, in such a manner as to transmit the movements of the rifle to the recording device when the marksman is aiming, the rifle being held in aiming position with the armature bearing against a 35 fixed point with respect to the rifle.

The target, which is supported by the armature, is preferably connected with a pointer the point of which makes the same movements as the target, but on a magnified 40 scale. At the end this pointer is provided with a needle, and while the fire arm is in motion, the said needle point moves over a surface which is an enlargement of the little target. Fixed into this surface (exchangeably) is a record sheet of paper or card 45 board which is jerked against the needle

point so as to be pierced thereby on the percussion needle of the rifle springing forward. The perforation thus produced is situated on the second sheet in a point corresponding to that one in which the line of sight of the rifle intersected the target at the moment of firing.

The apparatus is adaptable to all kinds of fire arms, due regard having to be paid, of course, to the variations in size, etc., involved by the differing dimensions of the arms that are to be used in connection with the apparatus. The apparatus in question is most suitable for certain types of manually operated fire arms and it is, perhaps, adapted to the best advantage in rifles, and will be described hereinbelow in connection with a rifle of Mauser-type.

The accompanying drawing shows an embodiment of the invention. Fig. 1 is a vertical longitudinal section of the apparatus. Fig. 2 is a cross section on line *a*—*b* in Fig. 1, and Fig. 3 a cross section on line *c*—*d* in Fig. 1. Fig. 4 shows the apparatus looking 50 from above, and Fig. 5 is a horizontal longitudinal section thereof. Fig. 6 represents the apparatus as connected with a rifle of Mauser-type.

According to the drawing, the frame of 55 the apparatus comprises a square casing 1 adapted to be fastened to the barrel 2 by means of two cross pieces 3—4 adapted to be slid thereon. Pivotally mounted in the part 4 is a clamp 5 with adjusting screws 6. According to Fig. 4, the clamp can be lowered behind the front sight 7 of the rifle so as to prevent the apparatus from being displaced. By screwing the adjusting screws 6 toward the front sight 7, the apparatus may be given such a position laterally that the vertical 60 central plane of the same coincides with a vertical plane through the line of sight of the rifle. Adjacent to the outer end of the apparatus there is provided within openings in the upper and lower sides of the casing a standard 8, which will be called "the armature" hereinbelow, the said standard being freely movable within the said openings, and provided with a foot-piece 9 at the 65 lower end thereof by means of which the standard or the armature may rest on a fixed support 10 (see Fig. 1). At its upper end the armature carries a disc 34 having represented thereon the image of a target 11 70 drawn to a highly reduced scale. The disk 34 and the target may be adjusted vertically

105
110

by means of a nut 13 threaded on the spindle 12 and bearing against the top end of the armature 8. The armature is connected with the casing 1 as well as with a pointer 14 by means of a gimbal so that the armature and the target can move both horizontally and vertically relatively to the casing, while the pointer 14 partakes of the motion so that the point 15 thereof moves over a record sheet 16 of paper or the like. This sheet of paper is inserted from one side into a frame 17 which is rigidly connected with a slide 23 adapted to be moved to and fro on the bottom of the casing 1. The above-mentioned gimbal consists of a horizontal shaft 18 arranged in the armature 8, the said shaft 18 being journaled in side pieces of a frame 19 belonging to the pointer 14. The frame 19 is movably connected with a vertical shaft 21 by means of a second horizontal shaft 20, the said shaft 21 being journaled between the upper and lower sides of the casing 1. One edge of the lower side of the casing 1 enters between the foot-piece 9 of the armature and an abutment 22 situated on the armature at some distance from the foot-piece, the vertical movements of the armature being thus limited so that the point 15 of the pointer 14 cannot strike against the casing at the top and the bottom thereof; the point 15 of the pointer is thus prevented from being injured. In the same manner the point is prevented from striking laterally against the casing, in that the horizontal movements of the armature are limited by the edges of the opening in the bottom of the casing (see Fig. 3).

At the bottom of the casing an arm 25 is rotatably mounted around a stud 24, a cord 26 being stretched between the one projecting end of the said arm 25 and the percussion needle 27 of the rifle. Pivotaly attached to the arm 25 by means of a stud 28 is a hook 29 adapted to be brought in engagement with an abutment 30 in the slide 23 when the percussion needle 27 is brought under tension and causes the arm 25 to be turned by a pull on the cord 26. The hook 29 is actuated so as to be brought in engagement with the abutment 30 by a spring 31 inserted between the hook and the slide 23. This spring also actuates the slide 23 and tends to displace it toward the rear end of the casing when the arm 25 bears against the fixed part 4 under the action of a spring 33 inserted between the stud 28 and a rigid pivot 32.

The action of the hook mechanism is as follows:—When the percussion needle or hammer 27 is pulled rearwardly in the act of cocking the firearm, a rearward pull is exerted upon the cord 26 causing the arm 25 to swing rearwardly on its pivotal axis 24, thereby moving the hook 29 rearwardly, the rounded abutment engaging beak thereof

sliding rearwardly along the adjacent face of the abutment 30. Upon completion of the cocking movement of the percussion needle of the hammer or firearm, the rounded beak of the hook 29 lies behind the abutment 30 and is swung into engagement therewith to the position indicated in dotted lines in Fig. 5 by the tension of the spring 31. The hook 29 remains in this position relative to the abutment 30 as long as the percussion needle or hammer of the firearm is maintained in retracted or cocked position. When the rifle or firearm is fired, the percussion needle or hammer 27 is projected forwardly in the usual manner producing a slack in the cord 26 and permitting the arm 25 to swing forwardly under the influence of the spring 33, and the beak of the hook 29 engaging behind the abutment 30 causes the slide 23 and record sheet 16 to be advanced forwardly along with the arm 25 and the hook 29. During the forward movement of the record sheet 16 it is penetrated by the needle point 15. When the arm 25 comes to rest against the member 4 of the casing, the slide 23 is returned to its initial position by the tension of the spring 31, the abutment 30 again assuming a position somewhat to the rear of the beak of the hook 29, as indicated in full lines in Fig. 5.

The target 11 may, if desired, be placed on a somewhat larger plate 34 which latter may be provided around the target with a colour composition as natural as possible. A miniature landscape, a skirt of wood, rocks or the like will be found to be the most suitable. The said plate 34 is connected with the armature 8 by means of a spindle 12 as set forth hereinabove.

When the apparatus is brought in its position on the rifle, and the latter is kept freely in the air in aiming position, the weight of the armature will cause the latter and the target 11 to assume such a position that the line of sight of the rifle will fall immediately above the target, the point 15 of the pointer 14 being then directed toward some point above the record sheet 16. If the muzzle of the rifle is now lowered so that the foot-piece 9 of the armature is brought to rest on a fixed support 10, the result of this will be that the target 11 is at rest, whereas the muzzle of the rifle can be moved vertically and laterally, this motion causing the line of sight of the rifle to move over the whole target 11 simultaneously as the point 15 of the pointer 14 moves over the whole record sheet 16. The marksman then has a surprisingly good illusion of aiming at a distant stationary target. The perforation produced in the record sheet 16 as hereinabove described then shows the aiming of the marksman at the moment of firing.

As will be seen from the above, the move-

ments of the line of sight, while the target is standing still, is limited to somewhat more than the size of the target.

What I claim as new and desire to secure by Letters Patent of the United States is:—

1. An apparatus for target practice with fire arms including a casing attachable to a fire arm, an armature supported in the casing so as to be movable relative to the fire arm in all directions, a target element carried by the armature, a recording device, and means connecting the armature with the recording device so as to transmit the movements of the fire arm to the recording device when aiming the fire arm, the latter being held in aiming position with the armature bearing against a fixed point with respect to the fire arm whereby the target carrying armature remains fixed during aiming movement of the firearm.

2. An apparatus for target practice with fire arms including a casing attachable to a fire arm, a target movably mounted on the casing, a marker movable with the target, a record element movable against the marker, means normally tending to displace the record element toward the marker, means to releasably lock the record element in inoperative position, and means adapted to connect said releasable locking means with a movable part of a fire arm whereby the locking means is actuated to release the record element incident with the firing of the fire arm so as to make a record of the accuracy of the aim of the fire arm.

3. An apparatus for target practice with fire arms including a casing, a target movably mounted thereon, a penetrating element carried by the target and movable therewith, a penetrable element mounted in the casing

and adapted to engage the penetrating element whereby to record the accuracy of the aim of the fire arm, supporting means for the penetrable element, a pivotally mounted lever arranged in the casing, means carried by the lever for engaging the support to effect movement of the latter in one direction with the lever whereby penetration of the penetrable element is effected, means normally tending to actuate the penetrable element, and means connected with the lever and adapted for connection with the movable part of a fire arm whereby the lever is locked to prevent actuation of the penetrable element during aiming of the fire arm.

4. An apparatus for target practice with fire arms including a casing, armature mounted for universal movement on the casing, a target carried by the armature arranged to be sighted along the sights of the firearm, means for adjusting the target relative to the armature, and means for securing the target in adjusted position relative to the armature.

5. An apparatus for target practice for fire arms including a casing, a fire arm clamping member carried by the casing, and adjustable members carried by the clamping member engageable with a part of the fire arm whereby the casing is secured in position thereon and the position of the casing with respect to the fire arm may be varied.

In testimony whereof I affix my signature in presence of two witnesses.

EINAR ERIK ALM.
